[57] CLAIM

The ornamental design for the solar powered construction light, as shown and described.

DESCRIPTION

FIG. 1 is a top perspective view of a solar powered construction light showing my new design;

FIG. 2 is a bottom perspective view thereof;

FIG. 3 is a front elevational view thereof on a reduced scale, the rear being a mirror image of the front;

FIG. 4 is a side elevational view thereof on a reduced scale, the opposite side being a mirror image of that shown;

FIG. 5 is a top plan view thereof on a reduced scale; and,

FIG. 6 is a bottom plan view thereof on a reduced scale.

FIG. 3

FIG. 4

FIG. 5

FIG. 6
